UNITED STATES PATENT OFFICE.

ALEXANDER F. WINTERS, OF GRAND RAPIDS, MICHIGAN.

LATCH.

1,292,553.

Specification of Letters Patent. Patented Jan. 28, 1919.

Application filed May 23, 1918. Serial No. 236,215.

To all whom it may concern:

Be it known that I, ALEXANDER F. WINTERS, a citizen of the United States of America, residing at Grand Rapids, in the county of Kent and State of Michigan, have invented certain new and useful Improvements in Latches; and I do hereby declare the following to be a full, clear, and exact description of the invention, such as will enable others skilled in the art to which it 10 pertains to make and use the same.

The present invention relates to a latch construction, designed for use particularly in connection with the doors of refrigerators, though it is to be understood that the latch is generally applicable to all types of swinging doors to hold the same in closed position. The invention is concerned with many novel improvements in the construction shown in my former application for patent Ser. No. 210,973 filed January 9, 1918, whereby all of the parts going to make up the complete latch structure may be made entirely from stamped metal instead of casting the same as shown in said prior application. A further object and purpose of the invention consists in the provision of a novel bearing relation between the handle of the latch and the case or housing on which the handle 20 is pivotally mounted, whereby the latch cannot become distorted nor the handle shift in position with respect to the case due to strains imparted thereto, such as might otherwise occur without such bearing construction. Another object and purpose of the invention consists in the provision of a latch structure which may be made almost entirely of sheet steel making one very durable yet economical to construct. These and many other objects and purposes will appear fully as understanding of the invention is had from the following description taken in connection with the accompanying drawings, in which—

Fig. 1 is a side elevation of the latch and keeper used therewith, the latch being attached to the door and the keeper to the casing with the door in closed position.

Fig. 2 is a front elevation of the construction shown in Fig. 1.

Fig. 3 is an elevation of the latch from the rear side thereof.

Fig. 4 is a plan of the blank from which the handle and a striker lug is made.

Fig. 5 is a vertical section substantially on the line 5—5 of Fig. 2.

Fig. 6 is an upper end view of the latch, a fragment of the door being shown in section.

Fig. 7 is a rear view of the combined handle and striker lug as it appears before attachment to the latch casing.

Fig. 8 shows in plan, side elevation, and front elevation, the detachable bearing shoe associated with the handle inside of the casing.

Fig. 9 is a side elevation of a sheet metal member attached to the handle having a part adapted to pass through a slot in the case with which the shoe has detachable connection, and

Fig. 10 is a side elevation of the case before attachment of the handle.

Like reference characters refer to like parts in the several views of the drawings.

The keeper is permanently secured to the door casing or jamb 1 and is bent from a flat relatively thin bar of metal into the form shown at 2 in Fig. 1, terminating at its front portion in an upwardly turned part 3, 80 behind which the striker lug of the latch is adapted to locate when the door is in closed position. The keeper is attached to the door casing by screws or other suitable fasteners. The door 4 carries the latch which in construction comprises a base 5 with an outwardly projecting housing 6 formed integrally therewith, the housing being of curved outline and having a slot 7 in the central outer portion thereof. The base is secured to the door by a plurality of screws or other suitable fastening devices, being located closely adjacent the free vertical edge thereof and from the side of the housing, at the edge of the door, a part 8 is stamped, having a depending lip 9 which lies directly against the edge of the door as shown. In the side of the part 8 a central opening 10 is formed, the edges of which are serrated, as indicated at 11, for a purpose which will 95 later appear. The housing and base are drawn and stamped from a single piece of sheet metal, preferably, soft steel, though any other suitable metal may be used.

A handle 12 is pivotally mounted on the 105 housing. This handle, together with a striker lug adapted to pass over the upturned end 3 of the keeper, are formed from a single piece of sheet metal 13 of the form shown in Fig. 4. The handle at its upper 110 end lies directly over the housing 6 and has an inwardly extending ear 14 passing along-

side the part 8 of the housing heretofore described, while the striker lug 15 extends so as to pass across the meeting edges of the door and casing into position such that it 5 will lie behind the upturned end 3 when the door is in closed position, the lug being formed on its under side with an upwardly and inwardly inclined face 16 which strikes against the part 3 of the keeper as the door 10 is closed, riding over the upper end of the keeper the same as described in my former application for patent. The ear 14 is stamped with an opening to receive a pivot therefor and in the stamping a portion of 15 the metal is pressed beyond the surface of said part 14, forming an annular ring 17 around which a washer 18 may be located, disposed between the part 8 of the housing 6 and the depending ear 14 of the handle. 20 A tubular rivet 19 is used to pivotally connect the handle with the housing, it passing through the ear 14, the annular ring 17, and the opening 10 in the housing 6. A punch is used to spread the inner end of the 25 rivet forcing the metal thereof into the notches between the teeth at the edges of the opening 10, it being apparent that the rivet in this way is spread outwardly as indicated at 19^a in Fig. 3, and being of soft metal, such 30 as brass or the like, readily enters the notches 11 and becomes permanently connected to the casing so that the handle has a bearing on the rivet equal to the thickness of the ear 14 and the annular ring 17 stamped thereon. 35 On the inner side and at the upper end of the handle, a member of sheet metal is located, having a top 20 and two inwardly extending spaced apart legs 21 and 22, the former of which at its inner end is provided with oppositely extending projections 23 adapted to enter slots 24 formed in the upper and lower sides of the handle and striker lug member, and serving to reinforce the same and prevent separation of 40 adjacent edges of the completed handle and lug member when formed into shape from the blank shown in Fig. 4. The opposite leg 22 passes through the slot 7 of the housing and immediately below the inner surface 45 of the raised curved portion of the housing, a curved slot 25 is cut at its upper edge extending partially therethrough. This member is permanently secured in place to the handle by means of a rivet 26, though any 50 other suitable form of permanent connection may be used, spot welding for instance. A bearing shoe is located within the housing being formed from a piece of sheet metal and comprising a curved portion 27 slotted 55 a part of its length, as indicated at 28, at its free end. From the other end thereof a part 29 is bent to extend into the housing for a distance, integral with which two curved arms 30 are formed lying directly 60 above the part 29, the same, together with 65

the part 29 as a backing serving as a socket to receive one end of a coiled pressure spring 31. The opposite end of the spring is held by a hook formed at the end of a strip of metal 32 cut from the housing 6 when the slot 7 is formed; such metal being bent back into the housing, as shown in Fig. 5, to make the support for the upper end of the spring 31.

The bearing shoe is attached to the inwardly extending leg 22, its slot 28 passing to either side of the leg 22 back of the slot 25 therein, slot 25 in turn receiving that part of the shoe 27 above its slot 28, being held in position by the pressure of the spring 31. The handle is stopped in proper position by engagement of the leg 22 against the housing 6 at the lower end of the slot 7. It is apparent that on grasping the handle 12 and pulling outwardly thereon, the handle may be turned around the axis of the rivet 19, compressing the spring 31 and effecting the elevation of the striker lug 15 above the upturned end 3 of the keeper. It will be apparent in this connection that the shoe 27 bears against the under side of the housing 6 and no distortion of the handle with respect to the housing can take place, such as might otherwise occur were the only connection between the handle and the housing at the pivot 19 which is located as far 90 inwardly as possible.

From the foregoing, it will be apparent that I have constructed a latch capable of being formed entirely of stamped sheet metal, and one of especial strength and durability with the parts made of sheet steel, the rivet 19 and the washer 18 only being of brass. All movements at the pivot of the parts are of steel against brass which is desirable as increasing the useful life of the latch. This latch contains all of the features of merit outlined in the prior application for patent filed by me, to which reference has been made, including the simplicity 105 of action in opening and the substantial elimination of injurious strain on the hinges as the door is closed.

I claim:

1. In combination, a curved housing 115 formed with a slot in its outer portion, a depending handle having its upper end located over the housing, and provided with an inwardly extending ear lying alongside one side of the housing, means pivotally connecting the inner end of said ear to the side of the housing adjacent its inner edge, a member on the handle extending through the slot in the housing, a curved shoe on said arm bearing against the inner side of the housing, and spring means within the housing operatively associated with the handle tending to normally force its lower end inwardly, substantially as described.

2. In combination, a curved housing 130

- formed with a slot in its outer portion, a depending handle having its upper end located over the handle, and provided with an inwardly extending ear lying alongside one side of said housing, means pivotally connecting the inner end of said ear to the adjacent side of the housing at the inner portion thereof, a member on the handle extending inwardly through the slot in the housing, a curved bearing shoe on said arm lying closely adjacent the inner curved side of the housing, retaining means on the housing, and a coiled spring disposed between an end of the shoe and said retaining means tending to force the lower end of said handle inwardly, substantially as described. 5
3. In combination, a housing having a curved outline and provided with a slot in its outer portion, a depending handle having its upper portion located over the housing and pivotally connected to a side of the housing adjacent its inner edge, a member on the handle extending through the slot in the housing, a bearing shoe detachably connected to said member and riding closely adjacent the inner curved side of the housing, and yielding means in the housing associated with the shoe normally turning the lower end of the handle inwardly, substantially as described. 20
4. In combination, a housing of curved outline provided with a slot in its outer portion, a depending handle and laterally projecting striker lug formed from a single blank of sheet metal pivotally connected to a side of the housing adjacent its inner edge, the upper part of the handle lying over the housing and the lug projecting laterally therefrom over and substantially parallel to the axis of the pivot, said lug being formed on its under side with an upwardly and inwardly inclined surface, a member of sheet metal permanently secured to the upper end of the housing and extending through the slot, a bearing member on said first member riding against the under curved surface of the housing, and a spring in the upper portion of the housing and exerting force against said bearing member, substantially as described. 35
5. In combination, a housing of curved outline and provided with a slot in the outer portion thereof, a depending handle positioned with its upper end over the housing, an inwardly extending member at the upper end of the handle passing alongside the housing and having pivotal connection at its end to a side of the housing adjacent the inner edge thereof, a second member attached to the upper end of the handle and extending through said slot in the housing, a curved shoe connected with said member inside the housing and bearing against the curved inner side thereof, said shoe being above said second member and formed at its upper end with a socket, and a coiled spring seated at one end in the socket and pressing against the same, substantially as described. 55
6. In combination, a housing, a depending handle formed from sheet metal and including an integral inwardly extending ear lying along one side of the housing and a laterally extending striker lug the under side thereof being inclined upwardly and inwardly, said ear having an opening therethrough, an annular projecting ring pressed from the metal of the ear around the opening, a washer around the ring and located between the ear and side of the housing, a headed pivot passing through the opening in the ear and fixed to the side of the housing, and yielding means within the housing operatively associated with the handle to normally force its lower end inwardly, substantially as described. 70
7. In combination with a curved housing having a slot in its outer portion, a depending handle having its upper end located over the housing, and provided with an ear passing along one side of the housing, means pivotally connecting the inner end of said ear to the side of the housing adjacent the inner edge thereof, a member attached to the upper end of the handle and passing through the slot in the housing, said member within the housing being formed with a curved slot extending partially therethrough from its upper edge, a curved shoe also partially slotted from its lower end located on the inner side of the housing, said slots of said member and shoe serving to detachably interlock the same together, and a coiled spring in the upper portion of the housing pressing against the free upper end of the shoe, substantially as described. 75
- In testimony whereof I affix my signature.
- ALEXANDER F. WINTERS.
